UNITED STATES PATENT OFFICE.

WILLIAM N. PARK, OF CORNING, NEW YORK.

GEAR-SHIPPER FOR FARMING AND SIMILAR MACHINERY.

No. 919,067.

Specification of Letters Patent.

Patented April 20, 1909.

Application filed November 11, 1908. Serial No. 462,033.

To all whom it may concern:

Be it known that I, WILLIAM N. PARK, a citizen of the United States, residing at Corning, in the county of Steuben and State 5 of New York, have invented a certain new and useful Improvement in Gear-Shippers for Farming and Similar Machinery, of which the following is a specification.

My invention relates to a new and useful 10 improvement in gear shippers for farming and similar machinery, and has for its object to provide an exceedingly simple and effective device of this character whereby the gears may be thrown in engagement when the 15 driver sits upon the seat or they may be thrown out when the driver leaves the seat or falls from the same, thus should the driver fall from the seat in front of any of the working parts, said working parts would at once 20 be stopped thus saving the driver from being cut or injured by said working parts.

With these ends in view, this invention consists in the details of construction and combination of elements hereinafter set forth 25 and then specifically designated by the claims.

In order that those skilled in the art to which this invention appertains may understand how to make and use the same, I will 30 describe its construction in detail, referring by letter to the accompanying drawing forming a part of this specification, in which—

Figure 1 is a plan view of a part of the frame of some farming machine showing my 35 improvement applied thereto. Fig. 2, a side elevation thereof, and Fig. 3, a rear view thereof.

In carrying out my invention as here embodied, A represents the frame of a farming 40 machine suitably mounted upon the axle B on either end of which may be secured suitable wheels. To the frame A is secured the casing C or said casing may be formed therewith, and in the side of the casing is formed 45 the hole C'. On the top of said casing is formed the opening D through which extends the seat post E which is secured to the frame as indicated at F. On the outer end of this seat post is fastened the seat G. Pivoted to 50 the rear of the casing C is the bell crank lever H to one end of which is pivoted the lower end of the rod I, the upper end of said rod being fastened to the seat post as indicated by J. To the other end of the bell crank lever is

pivoted one end of the rod K the opposite 55 end being attached to the member L which is secured to the gearing of the machine.

M denotes a spiral spring one end of which is fastened to the upper surface of the casing 60 at its forward end, the opposite end of said spring being attached to the seat post E.

N is a pin which is fastened to the casing by means of a chain O.

In practice when the driver takes his place upon the seat his weight will cause the seat post E to move downward which will cause the rod I to do likewise which action will move the bell crank lever H so that it pulls the rod K in the direction shown by the arrow adjacent thereto, this will pull the member L inward which will bring the gears to mesh with one another or to throw them in gear. Should the driver leave or fall from the seat the action of the spring M will draw the seat post E upward and this will reverse 75 the movement of the rods I and K and the bell crank lever H so that the member L will be pushed outward throwing the machine out of gear which will at once stop the working parts. The pin N is to be used when the 80 driver desires to have the machinery thrown in gear but does not want to ride upon the seat, he then places said pin N in the hole C' so that it rests on the upper surface of the seat post E thus holding said seat post down 85 and the gears in mesh, or if the driver desires to ride yet keep the machinery out of gear he places the pin in the hole C' so that it rests on the bottom of the seat post thus holding said seat post up against the weight of the 90 driver.

Of course I do not wish to be limited to the exact details of construction here shown as these may be varied within certain limits without departing from the spirit of my invention.

Having thus fully described my invention, what I claim as new and useful, is—

1. In a gear shipper, in combination with the frame of a farming machine, of a casing 100 having an opening in the top and a hole in the side thereof, a seat post passing through said opening, the lower end being fastened to the frame, a seat secured to said seat post, a bell crank lever pivoted to the rear of the 105 casing, a rod connecting said bell crank lever with the under side of the seat post, a member connected to the gearing of the ma-

achinery, a second rod connecting said member with the bell crank lever, a spring one end of which is secured to the casing, the opposite end to the seat post, and a pin adapted to be placed in the hole, as and for the purpose set forth.

2. In a device of the character described, the combination with a frame of a farming machine, of a casing having an opening in 10 the top and a hole in the side, a seat post adapted to pass through said opening, the lower end being secured to the frame, a seat fastened on the opposite end of said seat post, a member attached to the gears of the 15 machine, a bell crank lever pivoted to the rear portion of the casing, a rod, one end of which is attached to the member, the opposite end to the bell crank lever, a second rod, one end of which is attached to the seat post, 20 the opposite end to the bell crank lever, and

means for drawing the seat post upward when the driver leaves the same.

3. In combination with the frame of a farming machine, of a casing having an opening in the top and a hole in the side thereof, 25 a seat post having a seat secured thereto, the lower end of the seat post being secured to the frame, a member attached to the gears of the machinery, a bell crank lever pivoted to the casing, means for connecting said bell 30 crank lever with the member attached to the gears, and means for connecting the bell crank lever with the seat post, as specified.

In testimony whereof, I have hereunto affixed my signature in the presence of two 35 subscribing witnesses.

WILLIAM N. PARK.
